UNITED STATES PATENT OFFICE.

ALBERT A. HUSEBY, OF CHICAGO, ILLINOIS.

PLANING-MACHINE.

Specification of Letters Patent. Patented Jan. 28, 1913.

1,051,594.

Application filed September 26, 1912. Serial No. 722,384.

To all whom it may concern:

Be it known that I, ALBERT A. HUSEBY, a citizen of the United States, residing at Chicago, in the county of Cook and State 5 of Illinois, have invented certain new and useful Improvements in Planing-Machines, of which the following is a specification.

This invention relates to the general art of wood planing machines, and has reference more particularly to that type of planing machine employed to effect a preliminary leveling and flattening of more or less irregular surfaces of boards or timbers which, in drying out, may have become 15 somewhat warped or bent. These machines comprise, essentially, a platform or table in which is mounted a rotary planing tool, and a series of rolls mounted thereabove between which and the surface of the table the stock 20 to be operated upon passes, said rolls both feeding the stock over the planing tool and holding it down into engagement with the latter and the table.

My present invention has to do more particularly with the feed mechanism of such machines; and the main objects of the invention are to provide a feed mechanism which will be more certain and reliable in action, which object I accomplish mainly 30 through an improved driving mechanism for such feed rolls; to provide a machine wherein the feed rolls shall be independently forced against the work by spring pressure which can be regulated as desired; to provide a construction wherein the feed rolls 35 can be quickly and easily adjusted to suit the thickness of the particular work being operated upon; and, generally, to simplify and improve both the structure and operation of machines of this character.

To these and other minor ends my invention consists in the novel parts and combination of parts in a planing machine of the character specified all as hereinafter 45 described and pointed out in the claims.

My invention, its mode of operation, and the advantages secured thereby will all be readily understood when considered in connection with the accompanying drawings, in 50 which—

Figure 1 is a top plan view of my improved machine partly in horizontal section, and with the top cover of the housing removed to disclose interior parts. Fig. 2 is 55 a transverse section on the line 2—2 of Fig.

1. Fig. 3 is a front elevation. Fig. 4 is a side elevation.

Referring to the drawings, 5 designates the front wall, 6 the rear wall, and 7 and 8 the side walls, respectively, of a rectangular housing that contains the feed mechanism, and is supported, preferably by wheels or rollers 9, upon a table or platform, the upper surface of which is indicated at 10, and within which table is journaled the 65 usual revolving planing cylinder (not shown), the working edges of which extend a slight distance above the surface 10 through a transverse slot in the latter, all as well understood in machines of this type. 70

Beneath the front wall 5 is a feed opening 11 through which the work, such as the timber 12 (Fig. 2), is passed through the machine. Said opening is guarded by a vertically adjustable cover plate or gate 13 that 75 is slidable over the outer surface of the front wall 5, and may be secured at any adjusted height by clamps 14 extending through slots 14' in said gate.

Journaled in and between the side walls 80 7 and 8 is a drive shaft 15. Loose on this shaft are a series of levers 16 arranged in mating pairs. The forwardly projecting arms of the levers of each pair are connected at their forward ends by a short shaft 17, 85 on which is journaled a pair of feed-rolls 18 that are rigidly united laterally by an interposed spur gear 19. The rearwardly extending arms of said levers are connected by a rod 20. Fast on the drive shaft 15, 90 between the hubs of the two levers of each pair, is a spur gear 21 that meshes with and drives the spur gear 19. Journaled in and between the side walls 7 and 8 above the rearwardly extending arms of the several 95 levers 16 is a cam shaft 22, fast on which are a series of cams 23 that overlie and are adapted to depressingly engage the rear ends of adjacent levers of adjacent pairs, as clearly shown in Fig. 1, each cam thus operating the right-hand lever of one pair and the left-hand lever of the adjacent pair.

One end of the cam shaft 22 projects beyond its bearing in the side wall 7 and has keyed thereto an operating lever 24 provided 105 with a sliding detent 25 coöperating with a segment rack 26 secured to the side wall 7. By the means last described the several cams 23 can be forced downwardly to rock the feed-roll levers 16 so as to raise the feed- 110

rolls to the height required by the thickness of the work to be passed through the machine. Journaled in and between the side walls 7 and 8 parallel with the shafts 15 and 5 22 is a third shaft 27, fast on which are collars 28, to which are rigidly secured downwardly extending spring arms 29, the free ends of which bear upon the outer ends of the forwardly extending arms of the levers 16, each spring arm engaging adjacent levers of adjacent pairs in the same way that each of the cams 23 engages adjacent levers of adjacent pairs. One end of the shaft 27 projects beyond its bearing in the 10 side wall 7, and has keyed thereon an operating lever 30 provided with a sliding detent 31 engaging a segment rack 32 secured to the side wall 7. By this means, after the several feed-rolls 18 have been raised to 15 the required height to accommodate the work 12, by actuating the lever 30 the springs 29 are forced downwardly so as to exert spring pressure upon the feed-rolls and cause the latter to grip or bite the work 20 12 with sufficient force to feed the latter over the planing cylinder. Pivoted to the inner sides of the side walls 7 and 8 are gate-raising levers 33, the forwardly extending arms of which project through holes 33' in 25 the gate 13, and the rearwardly extending arms of which underlie at their free ends the outermost cams 23. By this means, assuming that the clamps 14 have been loosened, the actuation of the lever 24 in a direction to 30 swing the cams 23 downwardly, raises the gate 13 substantially in proportion to the elevation of the feed-rolls, so that the operator has only to tighten up the clamps 14 after setting the feed-rolls for operation 35 40 upon a given size of work.

Power may be applied to the drive shaft 15 in any suitable way; Figs. 1 and 3 showing one practical form of power transmission. 34 designates a bracket casting rigidly bolted to the outer side of the side wall 8. In an upper bearing 35 of this casting is journaled a pulley shaft 36, carrying on its inner end, a stepped pulley 37, and on its opposite end a spur pinion 38. The 45 pinion 38 drives a spur gear 39 keyed on a sleeve 4 (Fig. 1), which, in turn, is journaled on a bearing stud 41 secured in and projecting from the intermediate portion of the bracket casting 34. On the sleeve 40, 50 inwardly of the gear 39, is a spur pinion 42 that drives a spur gear 43 on the end of the drive shaft 15.

To protect the mechanism contained within the housing or casing, as well as to 55 protect the operator from possible injury therefrom, said housing or casing is preferably provided with a cover plate 44 removably secured to the side and end walls of the casing as by screws 45. The housing 60 and mechanism contained therein and car-

ried thereby is secured to the table or platform 10 by screws 46 mounted in lugs 47 on the side walls 6 and 7 and engaging tapped holes in said table.

In operating the machine, the operator 70 first sees that the clamps 14 are loosened and that the spring actuating lever 30 is in an inward position, wherein the springs 29 are elevated. The lever 24 is then actuated to raise, through cams 23, the feed rolls 18 to 75 a height slightly less than the thickness of the work to be operated upon, this, at the same time, raising the gate 13, to a sufficient height to admit the work. The clamps 14 are then tightened, and the spring actuating lever 30 is then thrown forward to 80 force the springs 29 hard down upon the outer ends of the feed roll levers, as shown in Fig. 2. As the work is then pushed forward, such of the feed rolls as engage the 85 work ride up over the upper surface of the latter, bearing thereon under the action of the springs 29, with sufficient force to feed the work through the machine.

I claim—

1. A feed mechanism for wood planing machines, comprising, in combination, a drive shaft, a series of levers pivoted side by side between their ends, feed-rolls journaled on the forwardly extending arms of said levers, cam mechanism engaging the rear ends of said levers to effect a raising movement of said feed-rolls, driving connections between said drive shaft and feed-rolls, and spring mechanism for forcing said feed-rolls 90 into gripping engagement with the work.

2. A feed mechanism for wood planing machines, comprising, in combination, a drive shaft, a series of levers pivoted on said drive shaft between their ends, feed-rolls journaled between the forwardly extending arms of adjacent levers, cam mechanism engaging the rear ends of said levers to effect a raising movement of said feed-rolls, driving connections between said drive 105 shaft and feed-rolls, and spring mechanism for forcing said feed-rolls into gripping engagement with the work.

3. A feed mechanism for wood planing machines, comprising, in combination, a drive shaft, a series of levers pivoted on said drive shaft between their ends, feed-rolls journaled between the forwardly extending arms of adjacent levers, cam mechanism 115 engaging the rear ends of said levers to effect a raising movement of said feed-rolls, coöperating spur gears on said drive shaft and feed-rolls, respectively, for driving the latter from said drive shaft, and spring mechanism for forcing said feed-rolls into 120 gripping engagement with the work.

4. A feed mechanism for wood planing machines, comprising, in combination, a drive shaft, a series of levers pivoted on said drive shaft between their ends, feed-rolls 130

- 5 journaled between the forwardly extending arms of adjacent levers, a cam shaft disposed above and parallel with said drive shaft, a series of cams fast on said cam shaft
5 adapted to depress the rear ends of said levers, a hand lever on said cam shaft, driving connections between said drive shaft and feed-rolls, and spring mechanism for forcing said feed-rolls into gripping engagement
10 with the work.
5. A feed mechanism for wood planing machines, comprising, in combination, a drive shaft, a series of levers pivoted on said drive shaft between their ends, feed-rolls
15 journaled between the forwardly extending arms of adjacent levers, a cam shaft disposed above and parallel with said drive shaft, a series of cams fast on said cam shaft adapted to depress the rear ends of said levers, an operating lever on said cam shaft, coöoperating spur gears on said drive shaft and feed-rolls, respectively, for driving the latter from said drive shaft, and spring mechanism for forcing said feed-rolls into
20 gripping engagement with the work.
6. A feed mechanism for wood planing machines, comprising, in combination, a drive shaft, a series of levers pivoted side by side between their ends, feed-rolls journaled on the forwardly extending arms of said levers, cam mechanism engaging the rear ends of said levers to effect a raising movement of said feed-rolls, driving connections between said driving shaft and feed-rolls, a shaft disposed above and parallel
25
- 30
- 35
- with said driving shaft, a series of spring arms fast on said last named shaft and at their free ends engaging the forwardly extending arms of said levers between adjacent feed-rolls, and a hand lever on said last named shaft for forcing said springs downwardly.
7. A feed mechanism for wood planing machines, comprising, in combination, a housing having a feed opening in its front wall, a vertically slidable gate guarding said feed opening, a series of feed-rolls and driving mechanism therefor in said housing, cam mechanism for elevating said feed-rolls to working height, and mechanism also operated by said cam mechanism for elevating said gate simultaneously with the elevation of said feed-rolls.
8. A feed mechanism for wood planing machines, comprising, in combination, a housing having a feed opening in its front wall, a vertically slidable gate guarding said feed opening, a series of feed-rolls and driving mechanism therefor in said housing, cam mechanism for elevating said feed-rolls to working height, and a pair of pivoted gate-raising levers engaging said gate at their forward ends and at their rear ends engaged and actuated by said cam mechanism.
